UNITED STATES PATENT OFFICE.

CLEMENT J. WERNER AND JOSEPH H. SMART, OF DORCHESTER, MASSACHUSETTS.

FINDER LIGHT.

Application filed March 4, 1922. Serial No. 541,228.

To all whom it may concern:

Be it known that we, CLEMENT J. WERNER and JOSEPH H. SMART, citizens of the United States, and residents of Dorchester, 5 in the county of Suffolk and State of Massachusetts, have invented an Improvement in Finder Lights, of which the following description, in connection with the accompanying drawings, is a specification, like letters 10 on the drawings representing like parts.

Our present invention is directed to a novel light holder, finder, switch and detachable and adjustable mirror.

Our invention is particularly directed as 15 an article for use in connection with automobiles or other electrically operated machinery or devices, one of the important features being the non-conducting construction of the holder.

20 A further important feature consists in the arrangement of the holder or handle, the light, and switch construction, this being of special importance in articles of this kind for quick operation—both on and off— 25 by means of the operator's hand which holds the handle, thereby leaving the other hand free.

While our non-conducting finder light is 30 suitable for use and is complete in itself, we have also provided a novel and quickly attachable and detachable as well as adjustable detecting apparatus for use in connection therewith. This feature is of particular importance in work about machines 35 or the like where inaccessibility renders such work difficult.

In carrying out our invention we provide 40 a suitable length of a handle or holder, preferably non-conducting and yet of sufficient strength to carry the light, conceal and protect the wires, be provided with our novel form of switch, and facilitate the positioning of the light at any point desired. This handle or holder may be of fiber, vulcanized 45 rubber, or other non-conducting material to eliminate all danger of the operator receiving shocks therefrom when working about electrical machinery, as well as to prevent all danger of fire by short circuiting or 50 arcing. To this holder the light and reflector attaching and adjusting means are assembled, as will be explained.

55 Referring to the drawings, illustrating a preferred embodiment of our invention, Fig. 1 is a side view of our improved device with the reflector attached;

Fig. 2 is a view at right-angles to that shown in Fig. 1, looking from the left of Fig. 1;

Fig. 3 is a view of the light and holder 60 with the mirror detached;

Fig. 4 is a cross-sectional view on the line 4—4 of Fig. 3; illustrating the construction of the switch; and

Fig. 5 is a further detail. 65

Our improved form of finder and holder can be of any suitable size, but as here illustrated is adapted for ordinary use and is of a convenient size, the entire weight being trivial so as not to tire the operator, a 70 further feature obtained by the non-conducting or fibrous handle.

Our apparatus consists in a tubular member or handle 1, formed to receive and carry the current conducting wires 2, which may 75 be of any suitable or desired length. One end of the tube may be enlarged slightly as shown at 3 to carry the socket (not shown) for the usual electric light bulb 5. At the opposite end is the switch which we have specially devised for use in connection with this apparatus. This switch is formed to fit within the shell of the tube or handle 1 and consists in a non-conducting tubular portion 6 carrying imbedded therein metallic conductors 7 and 8, spaced slightly 80 from each other. These conductors can be readily fitted into the tubular portion 6—the latter being preferably of fiber—by sawing a groove into the same and then 90 fitting the members 7 and 8 therein, as clearly shown in Figs. 4 and 5. The outermost portion of the member 6 is reduced in diameter to receive thereabout a brass 95 or other metallic conducting member 10, to which latter is threaded a handle 12, adapted to project outside of the tube 1 and through a slot or recess 15 formed in the end of the tube, as best illustrated in Figs. 2 and 3. The switch member 10 is in the 100 form of a clip or semi-circular member, with its ends spaced appropriately so that upon a slight movement of the handle 12 and hence partial rotation of the clip 10, the terminals 7 and 8 will be connected or disconnected as desired. A ferrule or finish 105 16 is added for convenience, appearance and to aid in holding the handle.

Our apparatus as thus far described is complete and useful for a finder light for 110 any apparatus and being non-conducting is of especial usefulness and importance in

working about an automobile or other machinery where electrical devices are employed. No danger to the operator is possible from the light coming in contact with 5 charged wires or portions of the machinery, owing to the non-conducting handle.

In order to still further equip this apparatus for usefulness, we apply a reflecting mirror thereto. To this end a tubular ferrule 20 having an interior diameter suitable 10 to fit over the enlarged portion 3 adjacent the light of the finder, is formed, which ferrule 20 is preferably metallic and may have strengthening ribs or grooves 21 and 22 and 15 which also is partially split lengthwise and transversely, as shown at 24 and 25, to afford a springlike grip upon the portion 3 of the handle. A pin 27 fitted in the handle is adapted to cooperate with a bayonet joint 20 groove 28 in the bottom of the ferrule, to facilitate, fitting and locking the ferrule 20 onto the handle.

Attached to the ferrule 20 is a boss 30, which may and preferably does consist in 25 a pair of flanges 31 and 32, these terminating in a round bearing to receive the shank of a bolt or stem 33. Preferably this stem is threaded and fits into a correspondingly threaded reinforcement or lug 34. The 30 head of the bolt, 36, affords a bearing on the opposite side of the upstanding flange, and a handle 38 facilitates the partial rotation of the same, to afford a clamping action or release thereof on the detachable mirror. 35 This mirror consists in any suitable reflecting surface and is designated generally at 40, including a back or holder to which is secured an arm 41. This arm 41 extends in the form of a gooseneck with an open slotted part adapted to fit over the stem 33 of the bolt and between the flanges 32 and 31. This construction is clearly shown in dotted lines in Fig. 1. With the mirror thus applied the handle 38 is partially rotated to 45 bind and clamp the slotted gooseneck end of the bracket 41 between the flanges 32 and 31, thus holding the mirror firmly in position, while permitting quick adjustment for the angle desired.

50 It will be noted that the entire apparatus is compact, neat, can be readily assembled for use and with the mirror detachable and the entire mirror holding ferrule removed,

facilitating packing, shipping and carrying. The slot 15 in the tube 1 affords an 55 automatic limit or stop to control the actions of the switch, and this switch is so positioned, designed and constructed that the operator, with one hand holding the apparatus, can turn the switch on or off with a 60 slight movement of the finger, and independently, thus freeing his other hand at all times. For work about an automobile, effecting adjustments, or any other work requiring light, peculiarly positioned and 65 quickly placed, our apparatus will be found of great usefulness.

With the ferrule 20 applied, and when the mirror is used, the ferrule preferably 70 slightly overlaps the bulb of the light 5, thereby protecting the same and also concentrates the rays of the light upon the mirror. To aid in this action, the interior of the ferrule 20 may be silvered or otherwise 75 coated to reflect the rays of light diffused thereagainst, thus concentrating the rays of light upon the mirror and thereby greatly increasing the efficiency of a small lamp.

Our invention is further described and 80 defined in the form of claim as follows:

A finder light of the kind described, comprising an elongated cylindrical handle member of non-conducting material, an electric light bulb removably secured thereto at one end, conductors included in circuit 85 with said bulb and extending through the interior of said handle, a switch included in circuit with said conductor and located within the handle at the end remote from the bulb, an operating handle for said switch extending laterally outward from the handle and rotatable about the longitudinal axis of the handle, said handle being provided with a circumferential slot 90 through which the operating handle of the switch extends and which limits the rotative movement of the operating handle, a cylindrical casing slidably mounted over the handle adjacent the bulb and provided with laterally extending lugs, and a protecting 95 mirror adjustably mounted in said lugs. 100

In testimony whereof, we have signed our names to this specification.

CLEMENT J. WERNER.
JOSEPH H. SMART.
